Primary Examiner — Ian Simmons*Assistant Examiner* — Yolanda Robinson(74) *Attorney, Agent, or Firm* — Muncy, Geissler, Olds & Lowe, P.C.(57) **CLAIM**

The ornamental design for a video laryngoscope, as shown and described.

DESCRIPTION

FIG. 1 is a front right perspective view of a video laryngoscope according to the present invention.

FIG. 2 is a front view of the video laryngoscope of FIG. 1.

FIG. 3 is a top rear perspective view of the video laryngoscope of FIG. 1.

FIG. 4 is a right side view of the video laryngoscope of FIG. 1.

FIG. 5 is a left side view of the video laryngoscope of FIG. 1.

FIG. 6 is a top front perspective view of the video laryngoscope of FIG. 1; and,

FIG. 7 is a rear bottom perspective view of the video laryngoscope of FIG. 1.

The broken lines in the figures show portions of the video laryngoscope that form no part of the claimed design.
